UNITED STATES PATENT OFFICE.

LOUIS N. MOSS, OF NEW YORK, N. Y.

MACHINE FOR MEASURING TEXTILE FABRICS, &c.

1,087,677.

Specification of Letters Patent. Patented Feb. 17, 1914.

Application filed April 10, 1912. Serial No. 689,731.

To all whom it may concern:

Be it known that I, LOUIS N. MOSS, a citizen of the United States, residing at the borough of Manhattan, city, county, and State of New York, have invented certain new and useful Improvements in Machines for Measuring Textile Fabrics, &c., of which the following is a specification.

My present invention relates to improvements on the class of machines for measuring cloth and flexible material set forth in Letters Patent No. 1,005,453, issued to me Oct. 10th, 1911, the objects being mainly to attain a freer "unwind" of the material to be measured, so as to practically eliminate all dangerous pull or tension that might otherwise stretch and impair certain delicate woven or textile fabrics, or interfere with the correct measurement thereof, and also to afford means whereby measurements of greater length may be made and indicated with more accuracy than heretofore.

Incidentally the invention also includes certain details in the construction and arrangement of the parts whereby the apparatus is rendered more simple and effective, all as hereinafter more fully set forth.

In the accompanying drawings, Figure 1, is an elevation of the right hand side of the machine; Fig. 2, a plan of the same, broken away centrally; Fig. 3, is a longitudinal section taken upon plane of line 3—3 Fig. 2, and looking toward the rear or left hand side of the machine; Fig. 4, is a diagram illustrating the method of threading or starting the unwind; Fig. 5, is a diagram illustrating the unwinding operation; Fig. 6, is a detail view with the worm, scale and guide rod broken away to show the miter gears and countershaft underneath.

I have found that while the "unwind" roll-supporting spindle blade which is a feature of my aforesaid Letters Patent is effective when properly manipulated, it requires skill and care to insert the spindle blade into the goods, which is objectionable not only on account of the time and high priced labor involved, but also on account of the danger of accidental injury to material, especially goods of delicate nature. For this reason I support the bolt C, of material to be measured upon a plurality of "unwind" rollers u, u, delicately and accurately mounted horizontally on ball bearings b, b, the material being threaded over and around said unwind rollers with the unwound por-

tion of the bolt suspended in a bight thereof, as indicated by dotted lines in Fig. 3, and in solid lines in the diagram Fig. 5. Two or more of these unwind rollers u, u, 60 may be employed for the purpose, as shown in the drawings, that number being sufficient for ordinary purposes and sizes of bolts of cloth. They afford convenient preliminary support for the bolt C, of cloth or other 65 flexible material to be measured, so that the operator has not to sustain the bolt bodily during manipulation preparatory to starting the unwind. This will be understood by reference to Figs. 3 and 4, in the first 70 named of which the bolt C, is shown as resting upon the rollers u, u, with the end of the cloth dropped inward. Owing to the fact that the unwind rollers u, u, are idlers, and mounted on ball bearings at that, it is 75 an easy matter to turn the bolt C, upon said rollers by hand sufficiently to form a loop or apron c, as shown in Fig. 4, into which the remainder of the bolt C, may be slid or dropped as indicated by the dotted lines 80 and arrow in said Fig. 4, after which the free end of the cloth is again passed over the unwind rollers u, u, and then under the intermediate guide and tension roller t, and over the measuring drum d, and finally to 85 the folding board f, as indicated by the dotted lines and arrows in Fig. 3. Thus two widths of the material composing the bolt C, pass over the rollers u, u, traveling in the same direction, first, the width descending 90 across and upon the rollers u, u, when the bolt is dropped into the preliminary loop or apron c, as illustrated in Fig. 4, and secondly, the continuation of the free end passed over said first width and said unwind rollers when said free end is threaded 95 through the apparatus, as in Figs. 3 and 5. Fig. 5, represents this unwind diagrammatically, by reference to which it will be understood that as the cloth is drawn forward 100 by the measuring drum d, the bolt C, will necessarily rotate within the bight c, of the cloth, thus unwinding itself, the unwind passing up over and across the rollers u, u, down again around the bolt to form the continuation of the original bight c, and again 105 upward and over said unwind rollers u, u, to the intermediate guide and tension roller t, &c., as before stated. I have found by experimental investigation that this tumbling of the bolt upon itself, as it were, 110 opens out and frees the material, and at the

same time affords just the requisite degree of back pull or resistance to afford the best results in the unwind,—the goods passing freely a second time over the unwind rollers 5 u, u , and then under the combined guide and tension roller t , to the measuring drum d .

By the use of a plurality of rollers spaced apart with relation to the maximum width, not of the cloth, but of the bolt thereof, I 10 am enabled to form a bight or loop c , of adequate space and capacity to insure a minimum of resistance and prevent the bolt binding or retarding itself during its rotation.

15 The operative parts are mounted upon and between side members or standards a, a , of a suitable frame work, including the up-rights a', a' , between which the contact roller i , is supported by means which tend 20 constantly to press it against the measuring drum as in my patent hereinbefore mentioned. The peripheries of both the contact roller i , and the drum d , may be faced with suitable contact cloth as set forth in my 25 said prior Letters Patent, to insure a firm hold on the goods to be measured.

In the present case I dispense with a delivery roller between the measuring drum and the folder board f , and feed the measured material directly from the drum d , to 30 the latter. In place of the delivery roller heretofore used as aforesaid, I employ a series of stripper fingers s, s , projecting upward from the cross bar a^2 , of the frame, on 35 which the folder board f , is fulcrumed, and having their upper ends protruding into peripheral grooves d', d' , on the measuring drum d , as will be seen by reference to Figs. 2 and 3. By this means the measured goods 40 is positively lifted and stripped from contact with the peripheral cloth surface of the measuring drum d , and all tendency to cling to the drum is counteracted. I also vibrate the folder board f , by means of a 45 pitman p , pivotally connected with said folder board f , and to a pinion p' , mounted upon a bracket a^3 , on the rear side frame a ,—said pinion p' , meshing with the spur wheel d^2 , upon the driving shaft d^3 , upon 50 which the measuring drum d , is mounted. The use of the gearing for vibrating the folder board f , renders the action of the latter more positive and uniform than the means disclosed in my said prior Letters 55 Patent.

An important change in my present construction enables me to use an indicating scale and mechanism of much greater length than in my prior construction, in which the 60 worm is driven directly by a miter gear on the driving shaft meshing with a corresponding miter gear on the worm. This necessarily limits the extension of the worm, and hence of the scale &c., to one side of 65 the power shaft. I obviate this difficulty

and utilize all the available space for the indicating mechanism by interposing a countershaft e , between the miter gear m , on the power shaft d^3 , and the worm w , which in this case is mounted in suitable bearing brackets a^4, a^5 , above the axis of the power shaft d^3 , and in lieu of a miter gear is provided with a spur gear w' , which meshes with a corresponding spur gear e' , (shown in Fig. 1) on the countershaft e , which latter is mounted in the brackets a^4, a^6 , in a line parallel to the worm w , but at right angles to the power shaft d^3 , and is provided with a miter gear e^2 , meshing with the miter gear m , on said power shaft. Thus by the use of the countershaft e , I am enabled to straddle the driving shaft d^3 , at right angles thereto, and to extend in parallelism the indicator worm w , scale o , and the guide rod n , upon which the pointer n' , travels, upon both sides of said shaft and thereby approximately double, more or less, the length of the indicating mechanism. As a result I am enabled not only to measure greater lengths of cloth at one reading of the index, but also to use a scale made in larger proportions, in which smaller subdivisions of a yard may be visibly indicated, all of which tends to clearness and accuracy of measurement. As a corollary I am also 95 enabled to use a worm having a coarser screw thread of steeper or quicker pitch, which is an advantage as affording greater durability and greater accuracy of engagement with the female-threaded under side 100 of the traveling pointer n' , upon the guide rod n , said pointer n' , being made to swing into and out of engagement with the indicator worm w , as in Letters Patent 1,005,453 hereinbefore referred to.

Another feature of my present invention consists in the use of edge feed guides g, g , arranged in conjunction with the unwind rollers u, u , in such manner as to insure the alinement of the goods unwound from the 110 bolt C , and prevent the latter having undue play or motion longitudinally as it rotates. Incidentally the guides g, g , form the side walls of a box or compartment into which the spool boards e' , of the bolts C , fall when 115 the latter are fully unwound, but they nevertheless perform a new and important function for which they are purposely spaced and arranged as related to said unwind rollers u, u . In other words they are 120 largely essential to the success of this method of unwind.

My cloth measuring machine is designed to be operated by hand as the surest and most convenient means of maintaining control and accuracy of measurement, and to this end the power shaft d^3 , is provided with a hand crank d^4 , by which the drum d , and spur wheel d^2 , may be rotated.

By my improved construction and ar- 125

angement of parts I practically eliminate all unnecessary tension or drag on the material and hence the resulting measurement is more certain and correct.

5 What I claim as my invention and desire to secure by Letters Patent is,

1. In cloth measuring mechanism of the character designated, the combination with the measuring drum and connections, of indicating mechanism consisting of a miter gear upon the driving shaft, a countershaft formed with a miter gear at one end meshing with that on the driving shaft, and having a spur gear at the other end, a worm 15 extending at right angles to the driving shaft and on both sides thereof and formed with a spur gear meshing with the spur gear on the countershaft, a scale and a pointer guide rod parallel to said worm and 20 a swinging pointer slidable on said guide rod, the under side of said pointer being female threaded to engage the worm thread, for the purpose described.

2. In cloth measuring apparatus of the character designated, the combination with the indicating mechanism, measuring drum and connections of the spaced apart unwind rollers u , u , disposed in the same horizontal plane and the intermediate guide and tension roller t , whereby the material to be 25 measured may be threaded over and around

said unwind rollers with the wound portion of the bolt suspended in a bight thereof and the unwound end of the cloth again carried over said unwind rollers and under said intermediate guide and tension roller to the measuring drum d , for the purpose and in 35 the manner shown and described.

3. In cloth measuring apparatus of the character described, unwind rollers disposed 40 in the same horizontal plane spaced apart to form a support substantially the width of the bolt, the bolt being suspended in a bight of the material, and a guide and tension roller independent of and separated from 45 said unwind rollers.

4. In cloth measuring apparatus of the character designated, spaced apart unwind rollers adapted to support a bolt resting thereon and over which the material is 50 designed to pass, and a guide and tension roller in the same horizontal plane as said unwind rollers whereby the material may be threaded over and around said unwind rollers with the unwound end again carried 55 over said unwind rollers and under the tension roller.
